DESIGN FOR AN OPTICAL DISPLAY STAND

Sverre Hokstad, Jersey City, N. J.

Application January 14, 1939, Serial No. 82,358

Term of patent 7 years

To all whom it may concern:

Be it known that I, Sverre Hokstad, a subject of the King of Norway and residing in Jersey City, in the county of Hudson and State of New Jersey, have invented a new, original, and ornamental Design for an Optical Display Stand, of which the following is a specification, reference being had to the accompanying drawing, forming part thereof, and in which:—

Figure 1 is a front perspective view of the article showing my design; and

Figure 2 is a transverse sectional view of the same.

I claim:

The ornamental design for an optical display stand, as shown.

SVERRE HOKSTAD.
